UNITED STATES PATENT OFFICE

SOL L. BUSCHMAN, OF NEW YORK, N. Y., ASSIGNOR, BY MESNE ASSIGNMENTS, TO METAL PACKAGE CORPORATION, OF NEW YORK, N. Y., A CORPORATION OF DELAWARE

WASTE RECEPTACLE

Application filed January 5, 1929. Serial No. 330,532.

This invention relates to garbage or other waste receptacles employing an outer container and an inner waste-receiving receptacle together with a cover hinged to the outer container.

The principal object of the invention is the production of a device of the above character which shall be simple in construction and which shall be provided with means for raising the cover and means for raising the inner receptacle, one of said means acting on the other one of said means to cause it to function.

Other and further objects and advantages 15 of the invention will appear from the subjoined description taken in connection with the accompanying drawings in which:

Fig. 1 is a section taken through a device made in accordance with my invention.

20 Fig. 2 is a bottom plan view of the device.

Fig. 3 is a view similar to Fig. 1 (partly broken away) and showing the cover and inner receptacle in raised position.

Fig. 4 is a front elevation of the lower 25 part of the container.

Fig. 5 is a section taken through a modification showing the cover in closed position.

Fig. 6 is a bottom plan view of the modification.

30 Fig. 7 is a view similar to Fig. 5 but showing the cover and receptacle in raised position.

Figs. 8, 9 and 10 are views similar to Figs. 5, 6, and 7 respectively but showing a further modification.

Figs. 11, 12, and 13 are also views similar to Figs. 5, 6, and 7 respectively but showing still a further modification.

40 Referring in detail to the drawings: 1 indicates the body of the container which is provided with curled upper and lower edges 2 and 3 respectively to present a smooth appearance. 4 indicates the cover which is hinged to the body as at 5 in any desirable manner. Said cover is provided with a rearwardly extending strap 6 having an extension 7. Fastened to the inner side of the body in any desirable manner are the angle pieces 8. These support an inner waste or garbage-receiving receptacle 9 provided with

the usual bail 10 for convenience of removing the receptacle from the container when so desired.

A mechanism has been provided for raising the cover and the inner receptacle 9 so that access may be readily had to its bail 10, this mechanism being constructed as to first partially raise the cover and then the inner receptacle so that there will be no contact between the two parts thus eliminating noise and possible injury to the parts or either of them.

The above mechanism comprises an actuator consisting of a horizontally disposed rock shaft 11 journaled near its ends in bearing openings in the wall of the container. The forward end of said rock shaft is bent and terminates in a foot treadle 12 while the rear end terminates in a crank arm 13 having a rearwardly extending extension 14. Said extension passes through an opening in a link 15 and it is prevented from disconnection therewith by means of a pin 16. The upper end of said link is hooked and extends through an opening in the extension 7 of the strap 6.

A receptacle actuator comprising a bar 17 is pivotally mounted in suitable bearings 18 fastened to the inner wall of the body of the container. The rear end of said bar extends through a slot in the container and terminates in a right-angled extension 19 which normally lies beneath but spaced apart from the crank 13.

When the cover 4 is closed the parts are in 85 the position shown in Fig. 1 and the inner receptacle 9 is seated on the angle pieces 8 and with the receptacle actuating bar 17 spaced a certain distance from the bottom of the receptacle 9. When the treadle 7 is pushed downwardly the rock shaft 11 is rotated and the cover 4 is partially raised due to the connection between the cover and the rock shaft by the link 15. After the cover has been raised a certain distance upwardly on its hinge, the crank arm 13 engages and presses downwardly on the right-angled extension 19 to rock the actuating bar 17 on its hinge and thereby force the inner end of the same 90 upwardly into engagement with the bottom 95 100 of the receptacle 9.

of the receptacle 9 so as to force the receptacle upwardly from disengagement with the angle pieces 8 and make it readily accessible for removal. When the cover is fully raised the 5 parts are in the position shown in Fig. 3. After the treadle 12 is released the reverse movements take place until the receptacle and the various parts of the actuating mechanism again assume the position shown in Fig. 1.

10 In the modification illustrated in Figs. 5 to 7 inclusive the cover 4 is provided with a downwardly extending strap 20 and the hooked end 21 of the link 22 extends through 15 an opening in said strap. In this case the link lies within the container 1 as illustrated. The link is provided at its lower end with a forwardly extending receptacle actuator 23 which is normally spaced apart from the receptacle which seats on the angle pieces 8 as in the preferred form of the invention.

20 A rock shaft 24 of the configuration shown in Fig. 6 is journalled in bearing openings in the wall of the container as in the previous case. Its forward end is provided with a treadle 25 and a portion of said rock shaft lies beneath the receptacle actuator 23. When the treadle is actuated the rock shaft 24 presses the link 22 upwardly to push the cover 25 upwardly on its hinge 5. After the cover has been raised a certain distance the actuator 23 is forced into engagement with the bottom of the receptacle to raise the receptacle out of engagement with the angle pieces 30. 35 until the parts assume the position shown in Fig. 7. When the treadle is released, as is obvious, the reverse movements take place and the receptacle and the actuating mechanism again assume the position shown in Fig. 5.

40 The modification shown in Figs. 8 to 10 inclusive is very similar to that of Figs. 5 to 7 inclusive the main difference being that the link 26 is positioned outside of the container and the hooked end thereof is hooked over a pin 27 carried by the cover 4. The cover is provided with an extension 28 which is pivoted to a bracket 29 fastened to the outer side of the container. The end of the link 26 extends inwardly into the container through a slot 30 in the rear wall thereof and it is provided with a receptacle actuator 31 as in the case of the modification shown in Figs. 5 to 7 inclusive. The rock shaft 24 is of the same configuration as in the modification just referred to and a portion thereof extends beneath the receptacle actuator 31, said actuator being normally spaced apart from the receptacle as in the previous case. The cover 55 and receptacle are raised by a pushing movement as is obvious when the treadle 25 is actuated and it is thought the operation of the mechanism requires no further detailed description.

60 In the modification shown in Figs. 11 to

13 inclusive the cover 4 is pivotally fastened to the bracket 29 and the link 26 is connected to said cover in the same manner as in the modification of Figs. 8 to 10 inclusive. A 70 cover actuator bar 32 extends through slots 33 and 34 in the rear and front portions respectively of the container body, said actuator being pivotally connected to the lower end of the link 26 and pivotally mounted substantially centrally of the container to a 75 supporting bar 35 the ends of which are supported in the container body. 36 indicates a crank the ends of which are journalled in suitable openings in the wall of the container said crank being provided with extensions 37 which normally are spaced from the receptacle 9. The forward end of the actuator bar 32 is provided with a treadle 38 which, when pressed down, first partially raises the cover due to the connections just described and then engages the crank 36 to rotate the same and swing the extensions 37 upwardly into engagement with the receptacle 9 to force the same upwardly from disengagement with the angle pieces 8. 90

What I claim as my invention is:

1. In a device of the character described, a container, a hinged cover thereon, a receptacle supported within said container, a shaft supported by the wall of said container for raising said cover and having a foot actuated treadle extending from said container and a bar within said container normally separated from said shaft and adapted to be actuated by said shaft to raise said receptacle. 95

2. In a device of the character described, a container, a hinged cover thereon, a receptacle supported within said container, a foot actuated shaft supported by said container for raising said cover, connecting means between said cover and said shaft and means pivotally mounted in said container for raising said receptacle and adapted to be actuated by said shaft. 100

105 3. In a device of the character described, a container, a hinged cover thereon, a receptacle supported within said container, a foot actuated shaft supported by said container for raising said cover, connecting means between said cover and said shaft and means pivotally mounted in said container for raising said receptacle and adapted to be actuated by said shaft after said shaft has been moved a predetermined distance in its travel. 110

115 4. In a device of the character described, a container, a hinged cover thereon, a receptacle within said container, means within said container for supporting said receptacle, a foot actuated shaft supported in the wall of said container, a link connecting said shaft and said cover whereby said cover will be raised when said shaft is actuated, a bar pivotally mounted in said container for raising 120

130

said receptacle and adapted to be actuated by said shaft after said cover has been partially raised.

5. In a device of the character described, a container, a hinged cover thereon, a receptacle supported within said container, a shaft journalled in the wall of said container and terminating at its rear end in a crank and at its forward end in a foot actuated treadle, a link connecting said cover and said crank, a bar pivoted within said container for raising said cover and extending through the wall thereof and adapted to be actuated by said crank.
15. 6. In a device of the character described, a container, a hinged cover thereon, a receptacle supported within said container, means for raising said cover comprising a link and a pivoted shaft having a treadle and means for raising said receptacle within said container comprising a movable bar disconnected from said shaft and treadle and adapted to be actuated upon movement of said shaft and treadle.
25. Signed at New York, in the county of New York, and State of New York, this 3rd day of January, A. D. 1929.

SOL L. BUSCHMAN.
